CLAIM

The ornamental design for a case for cleaner, as shown and described.

DESCRIPTION

FIG. 1 is a perspective view of a case for cleaner, showing our new design;

FIG. 2 is a front elevation view thereof;

FIG. 3 is a top view thereof;

FIG. 4 is a bottom view thereof;

FIG. 5 is a right side elevation view thereof;

FIG. 6 is a left side elevation view thereof; and,

FIG. 7 is an enlarged cross-section view taken along line 7-7 of FIG. 5.

The portions of the case for cleaner shown in broken lines form no part of the claimed design.
